US0D1005385S

(12) **United States Design Patent** (10) Patent No.: **US D1,005,385 S**
(45) Date of Patent: ** Nov. 21, 2023

(54) **SCANNER**

(71) Applicant: **PFU Limited**, Kahoku (JP)

(72) Inventors: **Motoshi Shibuya**, Kahoku (JP); **Yuka Saeki**, Kahoku (JP); **Norifumi Tonami**, Kahoku (JP); **Yoshiaki Mizukami**, Kahoku (JP)

(73) Assignee: **PFU Limited**

(**) Term: **15 Years**

(21) Appl. No.: **29/749,610**

(22) Filed: **Sep. 8, 2020**

(30) **Foreign Application Priority Data**

Apr. 17, 2020 (JP) 2020-007944

(51) **LOC (14) Cl.** **16-03**

CLAIM

The ornamental design for a scanner, as shown and described.

DESCRIPTION

FIG. 1 is a perspective view of a scanner showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken lines in the drawings are for the purpose of illustrating unclaimed portions of the scanner and form no part of the claimed design.

1 Claim, 4 Drawing Sheets
